UNITED STATES PATENT OFFICE.

JOHN A. NOBLE, OF FLORENCE, MASSACHUSETTS.

IMPROVED DAMPER FOR STOVE-PIPES.

Specification forming part of Letters Patent No. 44,109, dated September 6, 1864.

To all whom it may concern:

Be it known that I, JOHN A. NOBLE, of Florence, in the county of Hampshire and State of Massachusetts, have invented a new and Improved Stove-Pipe Damper; and I do hereby declare that the following is a full, clear, and exact description thereof, which will enable others skilled in the art to make and use the same, reference being had to the accompanying drawings, making a part of this specification, in which—

Figure 1 is a vertical central section of my invention; Fig. 2, a plan or top view of the same.

Similar letters of reference indicate like parts.

This invention relates to a new and improved damper for stove-pipes, by which the damper, when fully closed will admit of sufficient draft to cause the gases to be carried up the pipe, thereby preventing the escape of the gases into the compartment in which the stove is placed, the slight draft allowing but an extremely slow combustion of the fuel in the stove. The damper when open admits of a good draft, sufficiently so as to cause a proper combustion of the fuel without allowing the heat to escape up through the pipe into the flue.

The invention consists in using, in connection with a damper, a flaring or bell-shaped plate or base fitted within the stove-pipe at any desired point and having the damper placed over the orifice or opening of said plate or base, the axis of the damper being a short distance above the orifice, as hereinafter fully set forth.

A represents the bell-shaped plate or base, constructed of cast-iron, and fitted in the stove-

pipe with its flaring side downward, the lower end of the plate or base being in contact with the pipe, so that the opening in the upper and smaller end of the base affords the only draft-communication through the base. On the upper end of the base A there are at opposite points two bearings, a a, in which a shaft, B, is fitted, and on which a circular damper, C, is placed, the diameter of which is a little greater than that of the opening in the upper end of the base A. The shaft B passes through the stove-pipe and has a thumb-piece, D, on one end of it, by which the damper may be turned.

When the damper is in a horizontal position it is closed, but as the bearings a a are a trifle above the upper edge of the base, a space will be allowed between the damper and the base sufficient to afford sufficient draft to cause the gases to escape up through the pipe, but not sufficient to admit of a rapid combustion of the fuel. When the damper is turned in a vertical position, it is open and a requisite draft is obtained. The base A serves to prevent the heat from passing up the stove-pipe into the flue, and in that respect alone it is a great improvement over the ordinary damper.

Having thus described my invention, I claim as new and desire to secure by Letters Patent—

The damper C, in combination with a base or plate, A, of flaring or other form, so as to have an opening for the damper of smaller diameter than the latter, and the base or plate fitted snugly in the stove-pipe with the damper a short distance above its orifice or opening, substantially as and for the purpose specified.

JOHN A. NOBLE.
